(57) **CLAIM**

The ornamental design for a self-locking boot latch, as
shown and described.

DESCRIPTION

FIG. 1 is a top left perspective view of a first embodiment
of a self-locking boot latch showing our new design;

FIG. 2 is a bottom right perspective view thereof;

FIG. 3 is a front elevational view thereof;

FIG. 4 is a rear elevational view thereof;

FIG. 5 is a right side elevational view thereof;

FIG. 6 is left side elevational view thereof;

FIG. 7 is a top plan view thereof; and,

FIG. 8 is a bottom plan view thereof.

The broken lines in the drawings depict portions of the
self-locking boot latch that form no part of the claimed
design.
